US00D770345S

(12) **United States Design Patent** (10) **Patent No.:** **US D770,345 S**
Hult (45) **Date of Patent:** **** Nov. 1, 2016**

(54) **BRAKE ADJUSTER**

(71) Applicant: **Haldex Brake Products AB**,
Landskrona (SE)

(72) Inventor: **Bjorn Johan Niklas Hult**, Landskrona
(SE)

(73) Assignee: **HALDEX BRAKE PRODUCTS AB**,
Landskrona (SE)

(**) Term: **15 Years**

(21) Appl. No.: **29/530,372**

(22) Filed: **Jun. 16, 2015**

(51) LOC (10) Cl. **12-16**

(52) U.S. Cl.

USPC **D12/180**

(58) **Field of Classification Search**

(57) **CLAIM**

I claim the ornamental design for a brake adjuster, as shown
and described.

DESCRIPTION

FIG. 1 is a first perspective view of the claimed design;
FIG. 2 is a second perspective view thereof;

FIG. 3 is a top view of thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines in the drawings illustrate portions of the
brake adjuster that form no part of the claimed design.

1 Claim, 7 Drawing Sheets
